UNITED STATES PATENT OFFICE.

EDMUND S. CHURCH, OF DAYTON, OHIO, ASSIGNOR TO THE NATIONAL CASH REGISTER COMPANY, OF DAYTON, OHIO, A CORPORATION OF OHIO, (INCORPORATED IN 1906.)

AUDITING AND TOTALIZING MECHANISM.

1,118,185.

Specification of Letters Patent. Patented Nov. 24, 1914.

Application filed July 5, 1910. Serial No. 570,389.

To all whom it may concern:

Be it known that I, EDMUND S. CHURCH, a citizen of the United States, residing at Dayton, in the county of Montgomery and State of Ohio, have invented certain new and useful Improvements in Auditing and Totalizing Mechanism, of which I declare the following to be a full, clear, and exact description.

10 This invention relates to auditing machines for detachable accounting or accumulating devices. The detachable accounting devices may consist of small metal cases in which are mounted a plurality of denominational slides which may be adjusted to represent and accumulate amounts, but to adjust these slides a specially adapted machine or cash register is required. Such machines together with detachable accounting devices 15 are described in a pending application filed by E. S. Church on Oct. 11, 1906, Serial No. 338,502, and in other applications.

The present invention relates to means for printing the totals of amounts which are 20 accumulated by individual detachable accounting devices, and for accumulating and printing grand totals of a plurality of detachable accounting devices, and also to means for resetting these devices.

25 With these and incidental objects in view the invention consists in certain novel features of construction and combinations of parts the essential elements of which are set forth in appended claims and the preferred 30 form of embodiment of which is hereinafter described with reference to the drawings which accompany and form part of the specification.

Figure 1 is a transverse vertical section 40 with the cabinet omitted of a machine constructed according to this invention. Fig. 2 is a detail of a platen and its operating mechanism, together with its ribbon feeding devices. Fig. 3 is a detail of a cam and pitman 45 man for rocking a totalizer into and out of mesh with its actuating mechanism. Fig. 4 is a detail of a cam and pitman and alining device for the totalizer carrying frame. Fig. 5 is a detail of a restoring device for 50 certain carrying segments. Fig. 6 shows a cam and connections for resetting the transfer devices. Fig. 7 is a rear elevation of the machine with part of the mechanism omitted and the cabinet shown in section. Fig. 8 is a detail in side elevation of part of

the totalizer resetting mechanism. Fig. 9 is a detail of a device by means of which the detachable accounting device may be latched to the machine. Fig. 10 is a top plan view of the machine. Fig. 11 is a top 60 plan view of a detachable accounting device with its casing in section. Fig. 12 is a transverse vertical section of a detachable accounting device.

In the following detailed description the 65 various mechanisms relating to the invention will be described in the following order: First the construction of the detachable accounting devices will be briefly referred to; then the auditing machine will be described, 70 starting with slides which coat with slides of the detachable accounting devices and serve to position type carriers and segment gears, by means of which a totalizer of the machine is actuated; then the printing mechanism, in order to show how detailed records are made of the differential settings which the slides of the machine receive from the 75 detachable accounting devices; then the totalizer, with means for meshing and unmeshing the totalizer with its actuators; the manner in which the totalizer of the auditing machine is reset, and how upon resetting of this totalizer a record is printed of the 80 total accumulated by it; and finally the manner in which the detachable accounting devices are reset.

A detachable accounting device is illustrated in Figs. 11 and 12. It comprises a frame 1 within which is slidably mounted 90 a set of denominational slides 2. These slides are normally spring drawn to their outer or "nine" positions. The slides may be differentially positioned by coating slides of suitably constructed cash registers and 95 are locked in their set positions by a plate 3 which, for this purpose, is provided with a pointed flange 4 engaging notches 5 in the slides. When the slides are differentially positioned the plate 3 is rocked upon its 100 pivot 6 to release the slides by a plunger which is mounted in the operating machine and which enters an opening 7 in the casing of the device. The unlocking movement of the plate 3 is normally prevented by identifying blades 8, the upper edges of which are provided with notches 10 which are normally out of alignment with the flange 9, therefore, in order to unlock the denominational slides the blades 8 must be positioned 105 110

so that their notches register with the flange 9. The operating machines are provided with means for correctly positioning the blades.

5 As previously stated, the present invention relates to means for accumulating the totals of a plurality of detachable accounting devices together with means for printing individual totals and also the 10 grand total, and also to means for resetting detachable accounting devices. To accomplish these objects the auditing machine is provided with a plurality of slides 33 (Fig. 1) which are properly positioned to be engaged by the denominational slides of the 15 detachable accounting devices when these devices are inserted into an opening 11 of the auditing machine. By pushing a detachable accounting device into this opening the slides 33 are in consequence positioned in correspondence with the setting of the denominational slides 2. The slides 33 are normally held in their upper or zero 20 positions, as indicated in Fig. 1, by springs 25 12 and the farther the slides 2 are away from their zero positions the greater will be the extent of movement of the slides 33. These slides are provided with two sets of rack teeth 13 and 14 which respectively 30 mesh with segment gears 15 and 16. The segment gears 15 are secured to type carriers 17, therefore these type carriers will be set according to the extents of downward movement of the slides 33. The zero 35 character is normally at a printing line 18. One unit of downward movement of a slide 33 will bring the "one" character to the printing line, whereas nine units, or the full extent of possible downward movement 40 of a slide 33, will bring the "nine" character to the printing line.

The printing mechanism is illustrated in side elevation in Fig. 2. In this view a roll of detail paper 19 is shown and the 45 paper leads from this roll to feed rolls 20 and 21 and from these rolls between the type carriers 17 and a platen 22, out of the machine. The platen 22 is carried by a pair of members 24 which are slidably 50 mounted upon a shaft 25 and a rod 26, and are connected together at their rear ends by a rod 27. This rod passes through an arm 28 fast on a shaft 29 which shaft also carries rigidly an arm 30 extending between pins 31 and 32 of a bell crank lever 34 loose on shaft 29 and which carries a roller 35 coacting with a platen operating cam 36. The roller 35 is carried by an arm 37 which is pivoted to the bell crank lever 34 55 for the purpose of allowing a slight rocking movement of the arm around its pivot. It is limited in this rocking movement by pins 38 and 39 and the object of so mounting the roller 35 is to permit a quick action 60 65 of the platen by a spring 40 as soon as the

high part 41 of the cam passes the center line through drive shaft 42 and the roll 35. At such time the arm 37 rocks slightly in the direction indicated by an arrow 43 under the action of spring 40 carrying the 70 roller 35 well clear of the cam.

The paper feed rolls are rotated the required extents and at the proper time by a cam 46 which is carried by the drive shaft 42 and which operates a pitman 47 connecting this cam with a plate 48 which is loosely carried by a shaft 49 and is connected by a link 50 with an arm 51 loosely carried by a shaft 52 upon which is rigidly mounted the feed roll 21. The arm 51 is provided with a pawl 53 engaging a ratchet wheel 54 fast on the feed roll 21. The companion feed roll 20 is journaled upon an eccentric sleeve 55 around a shaft 56 and this shaft carries an arm which at the time of threading detail paper between the rolls 20 and 21 is rocked downwardly to carry the roll 20 away from the roll 21.

Printing is done through an ink ribbon 59 which passes between the detail paper 90 and the type carriers from an ink ribbon spool 60 to a spool 61, these spools being respectively carried by the shaft 49 and a shaft 62. These rolls are rigid with ratchet wheels 63 and 64 and are respectively actuated by pawls 65 and 66, one of which is carried by the plate 48 and the other by a lever 67 which is connected to the plate 48 by a link 68, therefore the lever 67 is also rocked upon the rocking of the lever 48 but only one of the pawls is in engagement at a time, the pawls being alternately rocked into and out of engagement for the purpose of reversing the direction of feed of the ink ribbon. 95 100 105

Pivot pins 69 of the pawls carry small arms 70 which are connected together by a link 71. This link may be reciprocated in a vertical direction for rocking one or the other of the pawls into engagement with its respective ratchet. In Fig. 2 the link is in its lower position with the pawl 66 in engagement and the pawl 65 out of engagement. The link is held in this position either by its own weight or a light 110 spring but may be moved upwardly for the purpose of reversing the engagement of the pawls by tensioning a spring 72 which connects the link 71 with a pin 73 on a toothed wheel 74. The spring 72 is alternately tensioned and released by rotating the wheel 74. This wheel is rotated at a rate which corresponds to the length of ink ribbon by a pin 75 which is carried by a ratchet wheel 76 and causes the wheel 74 to rotate one 115 tooth space upon each complete rotation of the ratchet wheel 76. The ratchet wheel 76 is actuated by a pawl 77 which is carried by an arm 78 and this arm is connected by a link 79 to the plate 48, the 120 125 130

rocking of which was previously explained. As there are twelve teeth to the particular ratchet 76 which is shown, it takes twelve operations of the machine to cause the wheel 74 to rotate one tooth space. For this reason a considerable number of operations of the machine is required in order to reverse the direction of feed of the ink ribbon.

Totalizer.—A totalizer 80 (Fig. 1) is adapted to accumulate the totals of any desired number of detachable accounting devices and to this end receives differential rotation from the segments 16 each time a detachable accounting device is inserted into the machine. It was previously stated how the segments 16 receive differential rotation from the slides 33. The totalizer does not mesh with its actuating racks 91 upon the down-stroke of the slides 33, but is meshed with the racks 91 during the return movement of the slides. To this end the driving mechanism controls means for locking the slides 33 for a certain period during each operation of the machine and means for meshing the totalizer 80 at this time. The operating mechanism is so arranged that after the totalizer is meshed the slides 33 become unlocked and are then restored to their zero positions thus causing the totalizer pinions to be rotated extents which correspond to the extents of movement of the slides 33.

The slides 33 are locked in their moved positions by means of alining pawls 81 which are carried by a shaft 82 and coat with toothed segments 83 which are rigid with the type carriers 17. The alining pawls 81 are all secured to the shaft 82 and this shaft also carries an arm 84 (Fig. 2) which is connected by a link 85, arm 86, shaft 87, arm 88, and pitman 89 (Fig. 1) to a cam 90 on the drive shaft 42. It may be seen from Fig. 1 that this cam is arranged to rock the alining pawls 81 into engagement with the segments 83 soon after the beginning of the operation of the machine, when the platen is operated. A cam 96 (Fig. 3) also causes a pitman 97 to be lifted thereby rocking the totalizer 80 into mesh with the actuating racks 91. The pitman 97 is connected at its lower end to an arm 98 fast on a shaft 99, to which a totalizer carrying frame 100 is rigidly secured.

It is not desirable to rely upon cam 96 for regulating the exact positioning of the totalizer when the cam rocks it into mesh with the actuating segments. An alining device (Fig. 4) is therefore provided, consisting of a pawl 188 coacting with a "V" shaped notch 189 in the totalizer carrying frame 100. After the totalizer is in mesh a cam 190 causes the pawl to enter the notch 189 and thereby centers the totalizer in the desired position preventing friction

between the totalizer pinions and the actuating racks. The connection between the cam 190 and the pawl 188 is by pitman 191, arm 192, and shaft 193.

While the totalizer is in mesh the pawls 81 are rocked out of engagement with the alining segments 83 and a rod 101 (Fig. 5), which is carried by arms 102 on the shaft 25, is rocked around this shaft far enough to cause the type carriers 17 to be restored to normal or zero position through engagement with upper edges 103 (Fig. 1) of the type carriers. When the type carriers are moved away from their zero positions upon the insertion of a detachable accounting device the rod 101 is carried upwardly through engagement with the upper edges of the type carriers. This rod is pivoted to a pitman 92 (Fig. 5) which is provided with a roll 93 coacting with a cam 94 which is carried by the drive shaft 42, but the cam is normally not in the path of the roll 93 and, therefore, does not interfere with movement of the pitman upon insertion of the detachable accounting devices. The racks 33 and segment gears 16, as they are geared to the type carriers, are returned to their zero positions with the type carriers and upon the return movement of the segments 16 the racks 91, which the segments carry, cause the desired rotation of the totalizer pinions. After the segments arrive at their home position the totalizer is rocked out of engagement and is in condition for the next operation of the machine at which time it is further differentially rotated in the same direction thereby successively accumulating the amounts which are carried by the detachable accounting devices.

As the totalizer successively accumulates various amounts it is necessary to provide transfer or carrying devices. Each totalizer pinion 104, except the pinion of highest order, carries two diametrically opposite pins 105 which serve to engage and actuate transfer devices each time a pinion completes ten units of rotation. These transfer devices include pawls 106 which are pivoted loosely upon a rod 107 of the totalizer frame and are normally held by springs at rest against pins 109 as indicated in Fig. 1, and are located in the same vertical planes with depressible plates 110 each of which is carried by the segment 16 which is of next higher denominational order than the pinion 104 which carries the pins 105 coacting with the particular transfer pawl 106. When a pawl is rocked rearwardly it causes the depression of the coacting plate 110 thereby rocking a pawl 111, which is carried by the segment 16, rearwardly as a shoulder 112 of the pawl engages the upper side of the depressible plate 110. The pawl carries a pin 113 which normally engages a shoulder 114 on its re-

spective rack 91 and, therefore, prevents movement of the rack relatively to the segment 16 under the action of a spring 115, but when the pawl is rocked rearwardly upon 5 transferring operations, the rack springs one tooth space relatively to the segment 16 and in the direction indicated by an arrow 117.

After the totalizer is unmeshed the racks 91, which are in tripped position, are 10 stored to their normal relation with the segments 16 by a rod 118 which extends across edges 119 of the racks and is carried by a pair of arms 120 (Fig. 6) on the shaft 26. This shaft also carries an arm 121 which is 15 connected by a pitman 122 with a restoring cam 123 on main shaft 42.

This transfer mechanism is not novel in the present invention, but forms part of the invention described in a patent application 20 filed by E. S. Church, Serial No. 539,834, on Jan. 24, 1910, and describing a machine especially adapted for department stores.

To reset the totalizer and to transfer its 25 settings to the type carriers so that the grand totals which it accumulates may be printed, the totalizer pinions are each provided with pawls 124 (Fig. 1) which, when the totalizers are normally operated in a forward direction as indicated by arrow 125, 30 idly slide around the periphery of totalizer shaft 126 but the totalizer shaft is provided with a plurality of notches 127 (Figs. 1 and 7) for the purpose of engaging the pawls upon resetting operations and backwardly 35 rotating the totalizer pinions to their home positions. These notches are not normally in the line of movement of the pawls 124, therefore in order to reset the totalizer it is necessary to shift the shaft 126 in a longitudinal 40 direction, so that the notches and pawls will come into coacting relation. This shifting of the shaft is accomplished by a yoked lever 128 (Figs. 7 and 8) which is secured to a stub shaft 129, and flanges 130 45 and 131 of which extend over the ends of the totalizer shaft 126. By rocking the lever 128 in the direction of arrow 132 the shaft 126 is slid in the totalizer frame 100 as desired for resetting purposes.

50 The resetting is accomplished by rotating the totalizer shaft 126 a half rotation oppositely to the direction indicated by the arrow 125 (Fig. 1) and while the totalizer pinions are in mesh with the racks 91 so that the type carriers will be set properly for printing the total. It is of course essential upon resetting operations that no detachable accounting device be in the opening 11 of the machine, because if it were, free action of 55 the segments 16 and the type carriers would be prevented. For this reason the machine is provided with a shutter 133 (Figs. 1 and 10) for the opening 11 which is under the control of lever 134 (Fig. 7) by which the 60 shaft 129 is rocked. A link 135 is pivoted

to the yoke 128 by a pin 136 and connects the yoke to an arm 137 on a shaft 138. This shaft carries an arm 139 which extends upwardly through a cut 140 (Fig. 10) in the shutter 133 which is slidably mounted on a top plate 141 of the machine by means of pins 142 which extend through a slot 143 in the shutter. When the lever 134 is rocked to the right the arm 139 forces the shutter over the opening 11. It is then impossible to insert 70 a detachable accounting device while the lever 134 is in its moved position. If a detachable accounting device is in place and it is attempted to shift the lever 134 to the right, the accounting device, of course, blocks movement of the shutter and, therefore, prevents the operation of the lever. For the purpose of rotating the totalizer shaft upon resetting operations, the shaft is provided with a gear 144 (Figs. 7 and 8) adapted to mesh with a segment gear 145 which is loosely journaled upon shaft 26 and is pivoted some distance outwardly of the shaft to a pitman 146 which is reciprocated twice upon each operation of the drive shaft by a cam 147 thereon. 80 Upon ordinary operations of the machine, when the totalizer shaft is in such longitudinal position that its notches 127 do not engage the pawls 124, the oscillation of the totalizer shaft as controlled by the segment 85 145 performs no function, but upon total printing or resetting operations the oscillation of the totalizer shaft causes the totalizer pinions to be reset to zero positions. This occurs while the totalizer is in mesh 90 with the racks 89, as previously stated, and the printing of the total is accomplished by the usual operation of the platen.

In order that upon resetting operations the downward movement of slides 38, as effected by a reverse rotation of the totalizer pinions, may occur before the operation of the platen and the restoring movement of rod 101 (Fig. 5), these operations are delayed more than would be necessary in the 105 more common operation of adding amounts to the totalizer. Also in the matter of engagement of the totalizer, resetting operations require that it be disengaged on the restoring movement of rod 101, while in 110 adding operations it is at such time engaged, but in order to make a single cam serve the purpose of engaging the totalizer on both operations, and also to simplify the mechanism, the cam 96 (Fig. 3) is arranged to 115 engage and disengage the totalizer twice upon each operation of the machine. The first meshing and unmeshing serves to hold the totalizer in mesh the correct length of time for ordinary operations of the machine 120 when detachable accounting devices are inserted. The second meshing and unmeshing at such times is merely idle. Upon total printing operations the first meshing of the totalizer is employed for setting the type 125 130

carriers and when set the total is printed but the totalizer pinions are brought back to their original positions before being unmeshed; upon the second meshing of the totalizer, the totalizer is reset and then unmeshed and left in its zero position.

The above arrangement, while economizing in mechanism, also permits a printing of a subtotal, as the resetting lever 134 may be shifted to its normal position after the first meshing and unmeshing of the totalizer, and when the drive shaft has made about one-half of a rotation.

The difference between the two operations of the totalizer, in one case upon ordinary operations of the machine and in the other case upon total printing operations, is that in the first case the totalizer must be held in mesh only upon the restoring of the differential mechanism while in the other case the totalizer must be held in mesh during the resetting of the totalizer, but it should be out of mesh upon the restoring of the differential mechanism. The first half of the cam 96 is formed to hold the totalizer in mesh during the restoring of the differential mechanism. The second half of the cam is, therefore, so formed that the totalizer will be held in mesh during the resetting of the totalizer pinions but out of mesh upon the second restoring of the differential mechanism, which occurs by the action of springs 12 (Fig. 1) when the alining devices 81 are caused to release the type carriers by high part 95 of cam 90 passing away from the roller on pitman 89. To state this differently; upon ordinary operations of the machine when a detachable accounting device is in the machine, the totalizer pinions are rotated upon restoring the differential mechanism to zero position. Upon resetting operations the totalizer pinions are backwardly rotated while the differential mechanism is moving forwardly, therefore if the totalizer pinions remain in mesh during the return of the differential mechanism, they will be rotated back to their former reading. This is what occurs during the first half rotation of the drive shaft upon resetting operations, but the continued rotation of the drive shaft causes another part of the cam 96 to rock the totalizer into and out of mesh, though this part of the cam 96 serves to hold the totalizer in mesh only during the up-stroke of the segment 145, and by this construction the totalizer remains in its reset position at the completion of the operation of the machine. Because of this arrangement the cam 147 is arranged to oscillate the segment gear 145 twice upon each operation of the machine, as may be seen from Fig. 8 which illustrates this cam.

The particular type carriers 17 which are controlled in their movement by the identifying blades of the detachable accounting

devices are provided with blank spaces which are opposite the printing line when in their home position, for the purpose of preventing an impression from these type carriers upon resetting operations.

In the particular machine shown there are six amount slides 33 but it is desirable to have two or three more totalizer wheels 80, to permit addition of large amounts properly. With the type of machine shown, additional rack segments 91 are provided for these higher wheels but these higher segments are operated only at times of total printing, and are connected with type carriers 18 in any desired manner, for example, by slides like 80 the amount slides 33. These higher wheels may be operated to retain transfers and are therefore provided with the usual type of transfer racks 91. It might well be, however, that if the carrying segments of these higher orders were free to move, a transferring movement of a rack 91 might, by inertia, displace its carrying segment 16. To prevent this false movement, these higher order segments 16 are normally 90 locked against movement by a flange 195 on an arm 194, journaled on shaft 29, this flange normally resting against edges 196 of these higher order segments 16. These segments must be permitted to operate to print a total from the totalizer properly, however, and to this end the arm 194 is actuated by the resetting lever 134 as its end rides in a cam slot 197 in an arm fast to the lever 134. Thus when the lever 134 is moved to cause 100 resetting of the totalizer, the flange 195 is withdrawn from the segments 16 and they may rise if necessary to print the total properly. Of course no transfer ever takes place at a table printing operation.

In order to distinguish the printed grand total from the totals of individual detachable accounting devices a special type carrier 198 (Fig. 8) is provided. This carrier is connected through a link 199, a lever 200, 110 and a link 201 to one arm of the yoked lever 128 and when this lever is shifted to the resetting position the type carrier 198 is rocked so that a special character 202 is brought to the printing line.

In order to prevent withdrawal of a detachable accounting device when one is in the machine and the drive shaft is rotating, the machine is provided with a latch 150 (Fig. 1) coacting with shouldered plates 151 120 of the detachable accounting devices. When one of the detachable accounting devices is inserted into the machine its front edge engages a roller 152 which extends across a shoulder 153 of a slide 154 which carries 125 the latch 150. The roller 152 is carried by an arm 155 which is pivoted upon a shaft 156 and normally held in its upper position, as shown in Fig. 1, by a spring 157. The insertion of the detachable device, there- 130

fore, through the roller 152 causes the slide 154 to lower, bringing its shoulder 158 beneath a flange 159 on an arm 160 which is carried by a shaft 161. Upon the downward movement of the slide 150 the arm 160 is rocked out of the path of the shoulder 158 against the action of a spring 162 (Fig. 9) which is extended between the top plate of the machine and an arm 163 on the shaft 161. This arm is pivoted at its outer end to a pitman 164 which carries a roll 165 extending into a race 166 of a cam 167. The race of the cam is broadened at the point of the roll 165 adjacent the cam in its normal position for the purpose of allowing movement of the arm 160 upon the lowering of the slide 154. By the above means the detachable accounting devices are latched within the machine. At the proper time the cam 167 causes the arm 160 to be rocked away from the shoulder 158, permitting the slide 154 to rise under the action of its spring 186 thereby permitting the detachable accounting device to be ejected from the machine by the arm 155 under the action of the spring 157, the latch 150 being rocked out of engagement with the shoulder 151 of the detachable device when a shoulder 168 of the latch engages a shoulder 169 of a spring pressed pawl 170. This pawl is permitted to rock upon its pivot against the action of its spring upon the inward movement of the latch 150 but is prevented from rocking when engaged by the shoulder 168, by a lug 171 on an arm which is fixed against movement upon a pin 173.

If it is desired to reset the amount slides of the detachable accounting devices at the time the totals of the same are printed, it is merely necessary to depress a key 174 which is carried by a slide 175 and is retained in its pressed position by a pin 176 which is carried by the slide and may be pushed into a hole 177 in the shank of the key. The depression of the key 174 causes its shank to enter a slot 178 in a plunger 179 between an end 180 of the slot and an arm 181 which projects into this slot. The arm 181 is carried by a shaft 182 and is oscillated upon each operation of the machine by a pitman 183 which connects an arm 184 on the shaft with a cam 185 on the drive shaft 42. If the key 174 is not depressed the arm 181 will idly slide in the slot 178 of the plunger but when the key is depressed the plunger will be projected forwardly into the opening 7 of the detachable accounting device causing its flanged plate 3 to be rocked out of locking engagement with the denominational slides 2. This occurs after the printing operation, but before the unlatching of the detachable accounting device. The springs 12 force the slides 33 to their upper or zero positions thereby caus-

ing the denominational slides of the detachable accounting device to be pushed to their zero positions against the action of their springs. When the detachable device is reset it is retained in the machine slightly longer than usual in order not to rely wholly on springs 12 to do the work of resetting but to permit restoring cam 94 (Fig. 5) to do the work if necessary. To provide for releasing the detachable device at the time required when it is reset, releasing cam 167 (Fig. 9) is constructed to operate pitman 164 a second time when the drive shaft has rotated about 225 degrees. On such resetting operation the first releasing operation of the cam is ineffective by virtue of the engagement of plunger 179 with the retaining device. Before the unlocking of the denominational slides of the detachable device the notches 10 in the identifying blades 8 must be brought to coacting relation with the flange 9 of the locking plate 3. This is accomplished by alining the type carriers which are under the control of the identifying blades 8. The alining of the type carriers is accomplished by pawls 186 (Fig. 2) which coact with alining segments 187 which are fixed to these type carriers. The pawls 186 are carried by shaft 82 the means for oscillating which was previously described.

While the forms of mechanism here shown and described are admirably adapted to fulfil the objects primarily stated, it is to be understood that I do not care to confine myself to any one form of embodiment of the invention here disclosed, for it is susceptible of embodiment in various forms all coming within the scope of the claims which follow.

What is claimed is:

1. In a machine of the class described, the combination with a detachable accumulating device manually insertible in the machine and comprising differentially adjustable slides with means for locking said slides in any adjusted position, of setting slides in the machine positioned to be engaged and actuated by said detachable device slides, rack segments driven by said machine slides, a totalizer, and connections for engaging the same with said rack segments, and devices for automatically releasing said slide locking means.

2. In a machine of the class described, the combination with a detachable accumulating device manually insertible in the machine and comprising differentially adjustable slides, of setting slides in the machine, positioned to be engaged and actuated by said detachable device slides when the same is inserted in the machine, means for positively restoring said setting slides to normal position, a totalizer, and connections for driving said totalizer by the restoration of said slides.

3. In a machine of the class described, the combination with a detachable accumulating device manually insertible in the machine, of means for latching said device when the same is inserted, setting slides positioned to be engaged and actuated by elements of said detachable device when the same is inserted, a totalizer, and connections for driving the same by restoration of said slides, and means for automatically releasing said latching device before said slides are restored.
4. In a machine of the class described, the combination with a detachable accumulating device manually insertible in the machine, and comprising differentially adjustable slides, of setting slides in the machine positioned to be engaged and actuated by said detachable slides when the same are inserted, type carriers geared to said setting slides, a platen positioned to take impressions from said type carriers, and means for positively restoring said type carriers and said slides to zero position.
5. In a machine of the class described, the combination with a detachable accumulating device manually insertible in the machine, of setting slides in the machine positioned to be engaged and actuated by elements of said detachable device when the same is inserted, a totalizer, and connections for driving the same by said slides, devices, including a hand lever, for printing the accumulation on said totalizer, and a shutter connected to said hand lever and moved thereby to prevent insertion of a detachable device in the machine.
6. In a machine of the class described, the combination with a totalizer including denominational elements, and means, including rack segments for operating said totalizer elements, of devices including a hand lever for printing the total accumulated on said totalizer, and an arm normally preventing movement of certain of said totalizer rack segments, with connections from said hand lever for displacing said arm whereby to permit movement of all said rack segments.
7. In a machine of the class described, the combination with a detachable accumulating device manually insertible in the machine and comprising differentially adjustable spring drawn slides, with means for locking said slides in any adjusted position, of a plunger for engaging and releasing said locking means, and operating device for said plunger having a lost motion connection therewith, with a manually adjustable element positioned when adjusted to take up the lost motion of said connection.
8. An auditing machine for self-contained detachable accumulating devices having denominational elements, comprising the combination of rack bars adjustable by said denominational elements, printing mechanism set by said rack bars, means for latching the inserted accumulating device in the auditing machine, and devices for releasing said latching means.
9. An auditing machine for self-contained detachable accumulating devices having denominational elements, comprising the combination of rack bars adjusted by a manual insertion of the accumulating device in the auditing machine, printing mechanism set by said rack bars, movable means for latching the accumulating device as it enters the auditing machine, means for preventing reverse movement of said latching means, and mechanism for disabling the preventing means and then releasing the latching means.
10. An auditing machine for self-contained detachable accumulating devices having denominational elements, comprising the combination with rack bars adjusted by a manual insertion of the accumulating device in the machine, and printing mechanism adjusted by said rack bars, of a slidable latch for holding said accumulating device, a device for holding said slidable latch against reverse movement, and means for releasing said holding means and said slidable latch in succession.
11. An auditing machine for self-contained detachable accumulating devices having denominational elements, comprising the combination with rack bars adjustable by a manual insertion of the accumulating device in the auditing machine, of a latching device engaging and holding said accumulating device before the same has engaged the said rack bars, and mounted to be then moved by said accumulating device, an arm constructed to engage and hold said latching device after the same has been moved by said accumulating device, and means for displacing said arm and said latching device in succession.
12. An auditing machine for self-contained detachable accumulating devices having denominational elements, comprising the combination with a totalizer, and means for actuating it under control of a detachable accumulating device when the same is inserted in the auditing machine, of means for printing totals from said totalizer, and a shutter moved by an element of said total printing means to a position preventing insertion of an accumulating device in the auditing machine.
13. An auditing machine for self-contained detachable accumulating devices having denominational elements, comprising the combination with a totalizer, and means for actuating it under control of a detachable accumulator when the same is inserted in the auditing machine, of means for resetting said totalizer to zero position, and devices moved by an element of said zero resetting

means to a position preventing insertion of an accumulating device in the auditing machine.

14. The combination with a machine including a totalizing device, of a totalizing device separate from said machine, mechanism in said machine adapted to coöperate with said separate totalizing device and the totalizing device included in said machine, to reset said separate totalizing device and to cause the totalizing device in the machine to accumulate the amounts of such resettings.

15. The combination with a detachable accounting device adapted to be reset, of a machine adapted to coöperate therewith comprising; a totalizing device, operating mechanism capable of transferring totals from said accounting device to said totalizing device, and manipulative means for determining whether or not resetting of the accounting device occurs on such operation.

16. In a machine of the class described, the combination with detachable accounting devices, and mechanical devices constructed to set them, of a machine having a totalizing device, adapted to be controlled to accumulate the amounts set in said accounting devices when successively inserted into the machine.

17. The combination with a detachable accounting device, of a machine adapted to coöperate therewith comprising; a manipulative device for controlling the operation of said machine, and means controlled by said manipulative device for preventing a coöperative relation between said accounting device and said machine.

18. In a machine of the class described, the combination with a detachable accumulating device, of mechanism adapted to coöperate with said detachable device to be controlled thereby, separate means for controlling said mechanism, said means having connections to prevent effective coöperation between said detachable device and said mechanism.

19. An auditing machine for self contained detachable accumulating devices having denominational elements, comprising the combination with a totalizer, and means for actuating it under the control of a detachable accumulator when the same is inserted in the auditing machine; and devices including a hand lever having a total position for printing the total accumulated on said totalizer and in coöperation with said actuating means turning the totalizer to zero if the hand lever when adjusted to its total position remains in such position until the end of the operation of the machine, but leaving the amount originally on the totalizer if the hand lever is moved out of its total position during the operation of the machine immediately after the printing of the total.

20. In a machine of the class described,

the combination with a totalizer, of printing mechanism for recording items entered on the totalizer and also the totals thereof, actuators for the totalizer normally disengaged therefrom and adapted to enter items thereon in an adding operation, or turn the same to zero, then restore on the same the amounts originally thereon and again turn the same to zero, or turn the same to zero and restore and leave on the same the amount originally thereon, and means for engaging and disengaging the totalizer from the actuators twice and at the same time at every operation of the machine, amounts being added on the totalizer in an adding operation during the first engagement and the totalizer in a total taking operation being turned to zero and then having the original amount restored thereon during the first engagement and subsequently turned to zero during the second engagement or turned to zero and having the original amount restored thereon during the first engagement and left thereon during the second engagement.

21. In a machine of the class described, the combination with a main operating mechanism of a totalizer, printing mechanism for recording the items entered on the totalizer and also the totals thereof, means operated by the main operating mechanism for engaging and disengaging said totalizer with said actuators twice at every operation of the main operating mechanism, means independent of said operating mechanism for adjusting said actuators in an adding operation, said actuators being adjusted in a total taking operation by said operating mechanism as controlled by said totalizer, and means actuated by the main operating mechanism during the first engagement of said totalizer with said actuators for restoring said actuators to normal to add amounts on the totalizer, said totalizer in a total taking operation being turned first to zero and then back to its original position during the first engagement of the totalizer with the actuators and turned to zero and left in zero position upon the second engagement of the totalizer with the actuators.

22. In a machine of the class described, the combination with a main operating mechanism, of a totalizer, actuators therefore for adding amounts on the totalizer and resetting the same, means controlled by the operating mechanism for always engaging and disengaging said totalizer with said actuators twice during each operation of the main operating mechanism, means independent of said operating mechanism for adjusting said actuators in an adding operation, and means actuated by the main operating mechanism for restoring said actuators during the first engagement of said actuators with the totalizer to add amounts

on the totalizer, the second meshing in turn to zero operations being employed to reset the totalizer when said actuators are not operated by said independent means, in that 5 operation of the machine.

23. In a machine of the class described, the combination with a detachable accumulating device manually insertible in the machine, of setting slides in the machine positioned to be engaged and actuated by elements of said detachable devices when the same is inserted, a totalizer, connections for driving the same by said slides, devices, including a hand lever, for printing the accumulation on said totalizer, and a shutter connected to said hand lever and moved thereby to prevent insertion of a detachable device in the machine, the presence of the detachable device preventing operation of the lever by the engagement of said shutter with said detachable device.
- 10 15 20 25 30 35

24. An auditing machine for self-contained detachable accumulating devices having denominational elements, comprising the combination with a totalizer, and means for actuating it under control of a detachable accumulator when the same is inserted in the auditing machine, of means for resetting said totalizer to zero position, and devices moved by an element of said zero resetting means to a position preventing insertion of an accumulating device in the auditing machine, the presence of a detachable accumulating device preventing movement of said devices and therefor of said element of said resetting means.

25. In a machine of the class described, the combination with a detachable accounting device, of a machine adapted to coöperate therewith, having a member with an opening for the insertion of the detachable accounting device and comprising a manipulative device for controlling the operation of said machine, and a plate moved

over said opening in the machine for preventing the insertion of said accounting device when said manipulative device is operated and for engaging said accounting device when inserted to prevent operation of said manipulative means when the account- 45 50 55 60 65 70 75 80

26. In a machine of the class described, the combination with an accumulating device comprising a plurality of differentially movable elements, a device normally locking the same against movement, means for resetting the accumulating device, operating means normally ineffective to release said locking means, and a depressible and slideable key manually depressible and slidably moved by said operating means to release said locking means.

27. In a machine of the class described, the combination with a detachable accumulating device manually insertible in the machine and comprising differentially adjustable slides, of setting slides in the machine positioned to be engaged and actuated by said detachable device slides when the same is inserted in the machine, devices for positively locking said setting slides in adjusted positions, a totalizer, actuators therefor normally disengaged therefrom and operated by said slides, means for positively restoring said slides and actuators to normal position to drive said totalizer, and mechanism for engaging said totalizer with said actuators while said locking devices for the slides are in locking position, the device being then rendered ineffective to permit restoration of the slides and actuators.

In testimony whereof I affix my signature in the presence of two witnesses.
